UNITED STATES PATENT OFFICE

LOUIS H. HOSBEIN, OF CHICAGO, ILLINOIS, ASSIGNOR TO M. H. DETRICK COMPANY, OF CHICAGO, ILLINOIS, A CORPORATION OF ILLINOIS

HANGER

Application filed February 20, 1930. Serial No. 429,876.

This invention relates to furnace arch construction and pertains particularly to an improved hanger construction designed for the supporting of heavy masses from the flanges of I-beams or other structural members having oppositely directed rigid flanges.

A general object of the invention is the provision of a simple and strong hanger, well qualified to resist weakening by heat and of such nature as to facilitate assembly with the supporting and supported members and admitting also demounting without involving the displacement of associated hangers or other portions of the installation.

Other objects will be pointed out or indicated hereinafter or will be apparent upon an understanding of the invention or its employment in practice.

In the drawing forming a part of this specification I illustrate one form in which the invention may be embodied, but it is to be understood that this is presented for purpose of illustration merely, as it may take various other forms, all within the scope of the appended claims.

In said drawings,

Fig. 1 is an elevational view of a hanger in position on an I-beam;

Fig. 2 is a similar elevational view showing a preliminary position of the hanger in the operation of mounting it on the beam;

Fig. 3 is a longitudinal sectional view of a portion of an arch structure illustrating a manner of employing the hanger; and

Fig. 4 is a top view of the hanger illustrated in Fig. 1.

In various forms of suspended arches for furnaces and the like, the refractories which constitute the arch are suspended by supporting members from a framework or from metallic beams which are disposed above the arch and which it is desirable be spaced above the arch in order that they may be afforded the requisite cooling to prevent their becoming overheated and losing their stiffness and tensile strength. The refractories in the arch are subject to wear by erosion and other influences attendant upon furnace operation, and it is desirable that the structure

afford facilities whereby the refractories may be replaced from time to time. In order that such replacements may be made in comparatively limited areas of the furnace arch, it is desirable that the various component sections or portions of the arch be independently supported so that such as need repair may be removed and replaced without involving an extensive demolition of the structure. The present invention provides a hanger which may be applied and removed very readily, and without involving displacement of portions of the structure which it is not desired to remove, and thus facilitates the making of repairs in a limited portion of the arch structure.

The nature of the invention may be ascertained readily from the example illustrated in the drawing. The hanger includes a beam-engaging member having oppositely disposed arm portions 10 and 11 which are connected by a yoke portion 12 that is provided with an aperture 12^a. At their other ends the arm portions are provided with overhanging lugs or shoulders 14 and 15 extending toward each other and spaced apart by a distance less than the width of the beam flanges for which the beam-engaging member is adapted. The arm 11 is bowed outwardly to an extent somewhat greater than the arm 10, so that its overhanging lug portion is somewhat longer than the opposite lug portion 14. On the arm 11 below the lug 15 is a stop shoulder 16, the end face of which is of approximately the same spacing from the axis of the aperture 12^a as is the inner face of the arm 10 adjacent the lug 14. The end face of the stop lug 16 and the inner face of the arm 10 adjacent the lug 14 are spaced apart a distance only slightly exceeding the width of the I-beam flanges for which the hanger is designed. The space below the stop lug 16 is adapted to accommodate one of the beam flanges when the beam-engaging member is applied to the beam in a laterally tilted position, as illustrated in Fig. 2, thus permitting the lug 14 to be displaced sufficiently to clear the opposite beam flange as the beam-engaging member is brought back to the upright position. Thus both flanges of the beam may be introduced into the span of

the beam-engaging member, so that the lugs 14 and 15 will overlie the opposite flanges, and when said lugs are resting on the beam flanges, the stop lug 16 and the inner side 5 of the arm 10 will prevent the beam-engaging member shifting laterally to a point where either of the lugs will be disengaged from the beam flanges. In this position, the aperture 12 is in a position vertically below the beam. The hanger bar or rod 17 may be connected at its lower end to an arch bar 18, or other tile-retaining member, upon which the arch refractories or tiles 19 are supported or suspended. The upper end of the hanger 10 rod 17 is inserted through the aperture 12 and retained against withdrawal by a nut 20 which rests upon the yoke 12. It is desirable that the aperture 12^a be of sufficient size in 15 excess of the rod 17 to permit the latter a limited extent of swinging movement. The engagement of the beam-retaining member on the beam flanges is such that it may be shifted longitudinally thereon, and that it may permit also of swinging or tilting movement 20 longitudinally of the beam. Thus the hanger affords a flexible or pendulous support for the arch portion which it carries.

A hanger of this construction is of particular advantage in that it may be placed at 30 any point on or removed from a beam which is already permanently installed, without involving displacement or adjustment of associated hangers. Because of the integral construction of the beam-engaging member, furthermore, it is particularly qualified for 35 heavy service and for use where clamping members and the like, involving adjustable features, are likely to be rendered inoperative by rust or dirt. A beam-engaging member of 40 the sort herein described may be formed simply as a unitary casting, requiring no finishing operations in order to qualify it for successful operation, and hence may be made quite economically in sizes and proportions 45 requisite to support quite heavy loads. Where the beam-engaging members must necessarily be of considerable size for supporting heavy masses, there is likelihood of 50 their interfering with removal of the arch portions if the space between the supporting beams is limited. By virtue of the completely 55 removable character of the beam-engaging members above described, the present invention obviates that difficulty.

55 What I claim is:

1. A hanger for furnace arches comprising 60 a beam-engaging member having oppositely arranged arms spaced apart and terminating in overhanging lug portions extending toward each other and spaced apart by a distance less than the width of the beam flanges for which the member is designed, one of said arms having a stop lug below the overhanging lug for cooperation with the opposite arm 65 to prevent the overhanging lugs shifting out

of engagement with the beam flanges, the arm affording space below said stop lug permitting the insertion of one of the beam flanges to a distance permitting the overhanging lug of the opposite arm to clear the 70 opposite beam flange.

2. A hanger for furnace arches comprising a beam-engaging member having arms connected at the bottom by a yoke portion and provided with overhanging lugs at the top, 75 said lugs extending toward each other and being spaced apart by a distance less than the width of the beam flanges for which the hanger is designed, a stop lug provided on one of the arms below its overhanging lug for cooperation with the edge of the beam flange, and means for attaching a supported body to the yoke.

3. A hanger as specified in claim 2 and wherein the vertical axis of said means is midway between the inner ends of the overhanging lugs.

In testimony whereof I have hereunto subscribed my name.

LOUIS H. HOSBEIN.
